CLUTCH CONTROL MECHANISM, PARTICULARLY FOR RECORD CARD CONTROLLED TABULATING MACHINES

Francis Guy Sydenham English, West Croydon, England, assignor to The Accounting & Tabulating Corporation of Great Britain Limited, London, England

Application January 11, 1933, Serial No. 651,201,
and in Great Britain February 12, 1932

9 Claims. (Cl. 192—02)

This invention relates to clutch control mechanism, particularly for record card controlled tabulating machines, and has for its object to provide a form of clutch control mechanism in which depression of a pedal causes engagement of the clutch, and subsequent depression of the same pedal causes disengagement of the clutch, so that if the clutch is disengaged it can be engaged by depressing the pedal, whereas if the clutch is engaged it can be disengaged by depressing the pedal.

The invention is particularly applicable to record card controlled tabulating machines but may be applied to the clutch mechanism of any machine.

According to the present invention clutch control mechanism comprises the combination with a spring influenced striker for the clutch of a removable stop and a hinged abutment mounted on the striker to engage the stop, a clutch control adapted to lift the abutment and permit clutch engagement, a latch hinged on the striker adapted to engage the stop as the abutment is lifted, and means connecting the control with the latch when engaging the stop, whereby on the next operation of the control the latch releases the stop, means operable to remove the stop when so released to re-engage the abutment, and resetting means associated with the clutch to be operative when the clutch is engaged, and adapted to engage the stop and through the agency of the abutment to actuate the striker to disengage the clutch.

Preferably the stop is carried on a pivoted lever and the resetting means is in the form of a cam co-operating with this lever, means being provided whereby the cam always stops with the co-operating lever in contact with the highest part of the cam whereby the clutch is positively held out of engagement by the engagement of the abutment with the stop, which is held in position by its lever resting on the high part of the cam.

To this end the high part of the cam extends over the greater part of the circumference of the cam, and a brake may be provided to bring the cam to rest in the desired position.

Where the invention is applied to a tabulating machine, however, it is found that no brake is necessary, since the load on the machine is sufficient to bring the cam to rest before the co-operating lever has left the high part thereof.

Preferably, an operative connection is provided between the clutch and the switch for controlling the source of power associated with the clutch,

this connection being such that the operator cannot open the switch without first disengaging the clutch, and cannot engage the clutch without first closing the switch.

The invention may be carried out in various ways, but one construction according thereto is illustrated diagrammatically in the accompanying drawings, in which:

Fig. 1 illustrates the clutch control mechanism in elevation, the parts being in the positions which they occupy when the clutch is disengaged.

Fig. 2 illustrates parts of the mechanism in the positions which they occupy when the clutch is engaged and the machine is rotating.

Fig. 3 illustrates the same parts of the mechanism in the positions which they occupy when the clutch is engaged, but the parts are set so that the clutch will be disengaged when the cam again engages with its co-operating lever;

Fig. 4 shows a cross sectional plan on the line IV—IV of Figure 1 illustrating the connection between the clutch and the switch for the source of power associated with the clutch;

Fig. 5 is an end elevation of the switch and its associated parts, and

Fig. 6 illustrates a form of brake mechanism for stopping the cam in the required position.

In the construction illustrated in the drawings the main shaft 1 of the machine carries a driving clutch member 2 freely mounted on the shaft 85 and rotatable from a source of power. The member 2 is adapted to be moved into engagement with a driven clutch member (not shown) secured to the shaft 1, the clutch itself forming no part of the present invention.

The clutch member 2 is adapted to be moved along the shaft 1 into engagement with the driven clutch member by means of a striker 3 pivoted between its ends at 4 and carrying a pin 5 engaging with a groove in the clutch member 2.

A spring 5a attached to the striker 3 at 6 tends to maintain the clutch parts in engagement, the spring 5a being anchored to a fixed pin 7 carried by the frame of the machine.

Pivoted to the lower end of the striker 3 on 100 a pin 8 is an abutment member 9 and a latch 10. The members 9 and 10 carry downwardly projecting teeth 9a and 10a respectively of triangular form. These teeth have one side substantially vertical and the other inclined, and the two vertical sides of the teeth face in opposite directions.

When the clutch is out of engagement as shown in Figure 1 the vertical face of the tooth 9a on the abutment member 9 bears against a stop pin 110

11 carried on a lever 12 pivoted to the frame of the machine at 13, and a roll on the lower end of this lever rests on the high part of a cam 14 which is driven through the agency of the clutch.

5 The connection between the clutch and the cam comprises a gear wheel 106 engaging with a worm on the shaft 1 and secured to a stub shaft 107 mounted in the machine frame. Also secured to the stub shaft 107 is a gear wheel 108 10 engaging with a gear wheel 109 attached to the cam shaft 14a.

The operative portion or high part of the cam 14 is of such a length that if the invention is applied to a tabulating machine, the cam will 15 always come to rest in such a position that the lever 12 is resting on the high part of the cam. This will be the case in any machine where the load on the machine is sufficient to bring it to 20 rest within about half a revolution of the cam shaft. Where the machine is of such a character that the cam shaft would tend to go on rotating for several revolutions after the clutch is disengaged, a brake must be provided to bring the cam to rest before the lever 12 has left the high 25 part of the cam.

Suitable brake mechanism is illustrated in Figure 6 wherein a brake drum 100 is secured to the cam shaft 14a and is provided with a co-operating brake shoe 101 attached to the end of a lever 102 pivoted between its ends at 103 to a bracket 104 attached to the machine frame. The upper end of the lever 104 is connected by a link 105 to the striker 3. Thus when the striker 3 moves to disengage the clutch the brake will be applied and when the striker moves to engage the clutch the brake will be removed.

Thus with the parts in the position shown in Figure 1, the clutch is disengaged and through the agency of the abutment 9 which, by means of its tooth 9a is resting against the stop pin 11, the spring 5a is prevented from moving the clutch into engagement, the lever 12 carrying the stop pin 11 being held up by the cam 14.

Disposed beneath the members 9 and 10 is a horizontal knock-off shaft 15 carrying a double lever 16, of which one arm carries a pin 17 which, when the clutch is out of engagement, is disposed beneath a downward projection 9b pivoted to the abutment at 9c. The other end of the lever 16 carries a pin 18 disposed below a hook portion 19 carried on a link 20. The link 20 is guided by means of a slot 21 on a pin 22 hereinafter described and the lower end of the link 20 is pivoted to an arm 23 on a cross shaft 24 which carries another arm 25 connected by means of a link 26 to a bell crank 27, to which is attached a pedal 28 for controlling the clutch.

When the pedal is in its normal position the hook portion 19 is located a short distance above the pin 18 for a purpose to be hereinafter explained. The latch 10 also carries a downward projection 10b pivoted to it at 10c, this projection 10b being slightly longer than the corresponding projection 9b pivoted to the abutment 9, for a purpose to be hereinafter explained.

A spring 16a normally maintains the lever 16 in the position shown in Figure 1 against a stop (not shown).

The two projections 9b and 10b are connected by a spring 29 which pulls them towards one another. Stops 9d and 10d carried by the abutment 9 and the latch 10 respectively are provided to hold the projections 9b and 10b in the positions shown in Figure 1 against the action of the spring 29. The abutment 9 and the latch

10 are also pulled downwardly by means of springs 30 which are anchored to the frame of the machine. In Figure 1 only one spring 30 is shown, the other spring being immediately behind it.

As already mentioned, Figure 1 illustrates the parts in the positions they occupy when the clutch is disengaged. In order to engage the clutch the pedal 28 is depressed against the action of a spring 20a connected to the link 20 through the intermediary of the pin 22 and anchored at its upper end on the pivot pin 4 for the striker 3. The spring 20a tends to maintain the pedal in its normal position. The depression of the pedal pulls the link 20 downwardly until the hook portion 19 engages with the pin 18. It may here be explained that the downward movement of the link 20 also moves the pin 22 downwards, thereby actuating other mechanisms which will be described later. Continued downward motion of the link 20 after engagement of its hook 19 with pin 18 causes the lever 16 to be rocked in a clockwise direction and the pin 17 thereon pushes up the abutment 9 through the agency of the projection 9b. The abutment 9 is raised until its tooth 9a is clear of the stop pin 11, whereupon the striker 3 is turned in a clockwise direction by its spring 5a and causes engagement of the clutch.

This movement of the striker 3 pushes both the abutment 9 and the latch 10 over to the left in Figure 1, the inclined portion of the tooth 10a on the latch 10 riding over the stop pin 11, whereupon the spring 30 associated with the latch 10 brings the latch down on the left-hand side of the stop pin so that the parts assume the position shown in Fig. 2. As soon as the clutch is engaged the machine commences to move and the cam 14 begins to revolve.

The lever 12 is acted upon by a spring 12a which tends to maintain it in engagement with the cam 14, but with the parts in the positions shown in Fig. 2 when the high part of the cam 14 leaves the lever 12, the latter cannot follow it since it is latched in the position shown in Fig. 2 by means of the tooth 10a on the latch 10. The machine, therefore, continues to revolve and the clutch remains in engagement. The position of the tooth 10a on the latch 10 is such as to hold the roll on the lever 12 clear of the cam 14 so that it is not struck by the latter as it revolves.

The movement of the abutment 9 and latch 10 to the left in Figs. 2 and 3 removes the projection 9b from above the pin 17 on the lever 16 and brings the projection 10b into engagement therewith, as shown in Figures 2 and 3. The removal of foot pressure from the pedal 28 allows the pedal to rise again under the action of the spring 20a so as to be ready for the next operation.

In order to stop the machine by disengaging the clutch, the pedal is again depressed and the ensuing rocking movement of the lever 16 in a clockwise direction lifts the latch 10 through the agency of its projection 10b, whereby the tooth 10a on the latch 10 is removed from the stop pin 11 and the spring 12a is allowed to move the lever 12 in a clockwise direction so that the roll on its lower end comes into the path of the high part of the cam 14.

In moving over to the left the stop pin on the lever 12 by riding over the inclined surface of the tooth 9a on the abutment 9, raises the abutment to permit the pin 11 to pass to the left-hand side of the tooth 9a which immediately drops

down again under the action of the spring 30, so that the parts assume the position shown in Figure 3.

When the high part of the cam again comes round, it will move the lever 12 over to the right and the stop pin 11 acting on the vertical face of the tooth 9a will push the abutment 9 over to the right, thereby rocking the striker 3 in an anti-clockwise direction and disengaging the clutch.

The cam comes to rest with the high part engaging the roll on the end of the lever 12, whereby the lever 12 and all the parts are maintained in the position shown in Figure 1 so that the clutch is positively held out.

The movement of the striker 3 in an anti-clockwise direction to disengage the clutch has also brought the projection 9b again into position above the pin 17 on the lever 16, so that a subsequent depression of the pedal 28 will cause re-engagement of the clutch in the manner already described.

In certain classes of tabulating machine, means is provided for stopping the machine on the passage of a specially perforated stop card, the sensing mechanism for the stop card being connected to the stopping mechanism of the machine. For example, the arm to which the stop card sensing pin described in Powers' U. S. patent specification No. 1,245,506 is connected may be secured to the knock off shaft 15 so that when a stop card is sensed, or no card is in the machine, the shaft 15 will be rocked so as to effect disengagement of the clutch in like manner as if the pedal 28 were depressed.

In such a machine, however, if the card supply becomes exhausted the machine will stop and if the pedal 28 be depressed and there are no cards in the machine, the machine will stop again after one revolution of the cam 14.

In order to permit the machine to run without any cards, the lever 16 may be freely mounted on the knock-off shaft 15, and an arm 32 carrying a pin 33 engaging under the left-hand end of the lever 16 may be secured to the knock-off shaft 15.

Thus rocking of the knock-off shaft 15 by means of the stop card sensing mechanism will rock the lever 16 and stop the machine, but if the machine is started without any cards being in it, the pedal 50 may be held depressed, thereby holding the abutment 9 raised so that its tooth 9a is clear of the stop pin 11 so that although the knock-off shaft 15 will rock at each cycle of the machine due to there being no card in the machine, this rocking of the knock-off shaft has no effect and the machine continues to run until the pedal is released.

In order that when the pedal 28 is held depressed in this manner the projection 10b shall not ride up on to the pin 17 whereby the machine 60 would be stopped, the projection 10b is made longer than the projection 9b, so that when the abutment 9 is held up by continued depression of the pedal, the side of the projection 10b rests against the pin 17, the projection 10b turning about its pivot to permit this.

Associated with the clutch is a switch 34 for cutting off current from the electric motor which drives the machine. This switch is arranged to be opened or closed by the operator, preferably by means of the pedal 28 and means are provided whereby the operator cannot move the switch to open position without first disengaging the clutch and cannot engage the clutch without first closing the switch.

To this end the vertical link 20 is provided with

a slot 21 through which projects a pin 22 on another substantially vertical link 35 of which the upper end is guided by means of a slot 36 on the pin 8 attached to the lower end of the striker 3. The pin 22 is guided in a slot (not shown) formed in a fixed bracket 38 disposed between the lever 20 and link 35. The lower end of the link 35 carries a pin 39 and projects through a slot 40 of varying width in a horizontal part 41 of the bracket 38 attached to the machine frame (Figure 4). This slot 40 is narrow at one end, and wide at the other, and the arrangement is such that the link 35 whose lower end passes through it moves downward to close the switch, which is of the tumbler type as shown.

The connection between the switch operating knob 43 and the link 35 is by means of a bracket 44 secured to the link 35 and between the arms of which the switch knob 43 is held.

When the switch 34 is closed and the clutch out, depression of the pedal 28 first pulls the switch operating link 35 down, owing to engagement of link 20 with pin 22, the pin 39 on its lower end passing through the wide part of the slot 40. Further downward movement of the pedal causes 100 link 20 to rock the lever 16, thereby permitting the clutch to engage.

The engagement of the clutch is effected by rocking the striker 3 and this movement rocks 105 the switch operating link 35 so that the pin 39 on its end moves until it is in register with the narrow part of the slot 40, thus holding the switch closed. The spring 20a is provided to return the pedal 28 to normal position independently of the switch. 110 The machine is stopped by again depressing the pedal 28 when the lever 16 will be rotated again, thereby permitting the cam 14 to move the clutch out of engagement. The movement of the striker 3 to effect this will rock the switch operating link 115 35 until the pin 39 on its lower end again comes opposite the wide part of the slot 40, whereupon a spring 31 pulls the switch operating link 35 upwards and opens the switch.

What I claim is:—

1. In a clutch control mechanism the combination with a spring influenced striker of a removable stop and a hinged abutment mounted on the striker to engage the stop, a clutch control adapted to lift the abutment and permit clutch engagement, a latch hinged on the striker adapted to engage the stop as the abutment is lifted and means connecting the control with the latch when engaging the stop, whereby on the next operation of the control the latch releases the stop, 130 means operable to move the stop when so released to re-engage the abutment, and resetting means associated with the clutch to be operative when the clutch is engaged, adapted to engage the stop and through the agency of the abutment, 135 actuate the striker to disconnect the clutch.

2. In clutch control mechanism the combination of a clutch disengaging member, means tending to hold the clutch in engagement, a latch normally holding the clutch out of engagement, 140 an abutment normally idle, but adapted to hold the clutch disengaging member disconnected from a source of power when the clutch is engaged, a control member, and operative connections between the control member, and the latch and the abutment, whereby if the control member is depressed when the clutch is disengaged, the latch is operated to release the clutch to permit engagement thereof, and the abutment is operated to hold the clutch disengaging member disconnected 150.

from its source of power, whereas if the control member is depressed when the clutch is engaged the abutment is operated to release the clutch disengaging member thereby causing disengagement 5 of the clutch and the latch is operated to hold the clutch out of engagement.

3. In clutch control mechanism the combination with a spring influenced striker of a removable stop and a hinged abutment mounted on 10 the striker to engage the stop, a clutch control adapted to lift the abutment and permit clutch engagement, a latch hinged on the striker adapted to engage the stop as the abutment is lifted and means connecting the control with the latch 15 when engaging the stop, whereby on the next operation of the control the latch releases the stop, means operable to move the stop when so released to reengage the abutment, a cam co-operating with the stop, means for driving said cam through 20 the agency of the clutch, whereby when the stop is released the cam engages the stop and through the agency of the abutment actuates the striker to disconnect the clutch, and means whereby on disengagement of the clutch the cam is arrested 25 with the active portion of its periphery in engagement with the stop.

4. In clutch control mechanism the combination with a spring influenced striker, of a removable stop and a hinged abutment mounted 30 on the striker, a tooth on said abutment adapted to engage the stop, a clutch control adapted to lift the abutment and permit clutch engagement, a latch hinged on the striker, a tooth on said latch, adapted to engage the stop as the abutment 35 is lifted, and means connecting the control with the latch when engaging the stop, whereby on the next operation of the control the latch releases the stop, means operable to move the stop when so released to reengage the abutment, 40 and resetting means associated with the clutch to be operative when the clutch is engaged, adapted to engage the stop and through the agency of the abutment actuate the striker to disconnect the clutch.

45 5. In clutch control mechanism the combination with a spring influenced striker, of a removable stop and a hinged abutment mounted on the striker, a tooth on said abutment adapted to engage the stop, a clutch control adapted to lift the abutment and permit clutch engagement, a latch hinged on the striker, a tooth on said latch, adapted to engage the stop as the abutment 50 is lifted, and means connecting the control with the latch when engaging the stop, whereby on the next operation of the control the latch releases the stop, means operable to move the stop when so released to re-engage the abutment, a cam co-operating with the stop, means for driving said cam through the agency of the 55 clutch, whereby when the stop is released the cam engages the stop and through the agency of the abutment actuates the striker to disconnect the clutch, and means whereby on disengagement of the clutch the cam is arrested with the active portion of its periphery in engagement with the stop.

6. In clutch control mechanism the combination with a spring influenced striker, of a removable stop and a hinged abutment mounted 70 on the striker to engage the stop, a control pedal, a downward projection on the abutment, a lever pivoted to the machine frame, a pin on said lever normally disposed beneath the downward projection on the abutment, an operative connection 75 between the pedal and said pivoted lever, where-

by when the pedal is depressed with the clutch out of engagement, the lever is rocked and its pin caused to raise the abutment and permit clutch engagement, a latch hinged on the striker, a downward projection on the latch, means for moving the abutment and latch, when the abutment is lifted, to bring the latch into engagement with the stop and the downward projection on said latch above the pin on the pivoted lever, whereby on the next depression of the pedal the latch is raised to release the stop, means operable to move the stop when so released to re-engage the abutment, and resetting means associated with the clutch to be operative when the clutch is engaged, adapted to engage the stop and through the agency of the abutment, actuate the striker and disconnect the clutch.

7. In clutch control mechanism the combination with a spring influenced striker, of a removable stop, and a hinged abutment mounted on the striker to engage the stop, a control pedal, a downward projection on the abutment, a lever pivoted to the machine frame, a pin on said lever normally disposed beneath the downward projection on the abutment, an operative connection between the pedal and said pivoted lever, whereby when the pedal is depressed with the clutch out of engagement, the lever is rocked and its pin caused to raise the abutment and permit clutch engagement, a latch hinged on the striker, a downward projection on the latch, means for moving the abutment and latch, when the abutment is lifted, to bring the latch into engagement with the stop and the downward projection on said latch above the pin on the pivoted lever, whereby on the next depression of the pedal the latch is raised to release the stop, means operable to move the stop when so released to re-engage the abutment, a cam co-operating with the stop, means for driving said cam through the agency of the clutch, whereby when the stop is released the cam engages the stop and through the agency of the abutment actuates the striker to disconnect the clutch, and means whereby on disengagement of the clutch the cam is arrested with the active portion of its periphery in engagement with the stop.

8. In clutch control mechanism the combination with a spring influenced striker of a removable stop and a hinged abutment mounted on the striker to engage the stop, a clutch control member connected with lost motion to the abutment and adapted to lift the abutment and permit clutch engagement a latch hinged on the striker adapted to engage the stop as the abutment is lifted, means for establishing a lost motion connection between the control member and the latch when the latch engages the stop, whereby on the next operation of the control member the latch releases the stop, means operable to move the stop when so released to re-engage the abutment, resetting means associated with the clutch to be operative when the clutch is engaged, adapted to engage the stop and through the agency of the abutment actuate the striker to disconnect the clutch, a switch controlling the source of power associated with the clutch, a switch operating lever pivoted between its ends by a pin and slot connection to the machine frame, an operative connection between the 145 striker and the switch operating lever whereby when the clutch is engaged or disengaged the switch operating lever rocks about its pivot, a locking device for the switch operating lever, a pin and slot connection between the control 150

- member and the switch operating lever whereby when the control member is moved to cause engagement of the clutch the switch operating lever closes the switch and is moved into a position 5 permitting said switch operating lever to engage with the locking device when said switch operating lever is rocked about its pivot due to the ensuing engagement of the clutch, means for returning the control member to normal position 10 leaving the switch operating lever locked, and means for moving the switch operating lever to open the switch when rocked clear of the locking device by disengagement of the clutch.
9. In clutch control mechanism the combination with a spring influenced striker, of a removable stop and a hinged abutment mounted on the striker to engage the stop, a control pedal, a downward projection on the abutment, a lever pivoted to the machine frame, a pin on said lever 15 normally disposed beneath the downward projection on the abutment, a lost motion connection between the pedal and said pivoted lever, whereby when the pedal is depressed with the clutch out of engagement, the lever is rocked 20 and its pin caused to raise the abutment and permit clutch engagement, a latch hinged on the striker, a downward projection on the latch, means for moving the abutment and latch, when 25 the abutment is lifted, to bring the latch into engagement with the stop and the downward projection on said latch above the pin on the 30
- pivoted lever whereby on the next depression of the pedal, the latch is raised to release the stop, means operable to move the stop, when so released, to re-engage the abutment, resetting means associated with the clutch, to be operative when the clutch is engaged, adapted to engage the stop and through the agency of the abutment, 35 actuate the striker and disconnect the clutch, a switch controlling the source of power associated with the clutch, a switch operating lever pivoted between its ends by a pin and slot connection to the machine frame, an operative connection between the striker and the switch operating lever whereby when the clutch is engaged or disengaged the switch operating lever rocks 40 about its pivot, a locking device for the switch operating lever, a pin and slot connection between the pedal and the switch operating lever whereby when the pedal is depressed to cause engagement of the clutch the switch operating lever closes the switch and is moved into a position permitting said switch operating lever to engage with the locking device when said switch operating lever is rocked about its pivot due to the ensuing engagement of the clutch, means for returning the pedal to normal position 45 leaving the switch operating lever locked, and means for moving the switch operating lever to open the switch when rocked clear of the locking device by disengagement of the clutch. 50
